UNITED STATES PATENT OFFICE

KENNETH S. PARKER, OF JANEVILLE, WISCONSIN, ASSIGNOR TO THE PARKER PEN COMPANY, OF JANEVILLE, WISCONSIN, A CORPORATION OF WISCONSIN

DESIGN FOR A FOUNTAIN PEN

Application filed July 8, 1929. Serial No. 31,965. Term of patent 14 years.

To all whom it may concern:

Be it known that I, KENNETH S. PARKER, a citizen of the United States, residing at Janesville, county of Rock, State of Wisconsin, have invented a new, original, and ornamental Design for Fountain Pen, of which the following is a specification, reference being had to the accompanying drawing, forming a part thereof.

In the drawing,—

I claim:

The ornamental design for a fountain pen, as shown.

KENNETH S. PARKER.
